GALLEY IDENTIFICATION HOLDING DEVICE

Joseph J. Schimmel, New York, N. Y.

Application August 28, 1940, Serial No. 354,468

7 Claims. (Cl. 40—10)

This invention relates to new and useful improvements in a galley identification holding device and a blank for the manufacturing thereof.

More specifically the invention proposes a galley identification device which is formed from one sheet of metal bent into a certain shape so as to have several operative portions. One of these portions comprises a jaw device for gripping the side wall of the galley tank and another one of these portions comprises an arm for engaging against the type slugs in the galley to hold the type slugs in position.

Still further the invention proposes to so construct the metal body that it is of a rigid shape capable of securely holding the type in position.

Still further the invention contemplates providing the body with several openings to facilitate the fingers gripping the body so that it may be easily removed.

Another object of the invention resides in a novel construction of the body to adapt it to hold a slug or individual pieces of type to identify the galley.

Still further an arrangement is proposed whereby the operative length of the body may be extended to extend across more than one column of type in the galley when this is required.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a galley provided with an identification holding device constructed in accordance with this invention.

Fig. 2 is a fragmentary transverse vertical sectional view taken on the line 2—2 of Fig. 1.

Fig. 3 is a plan view of the identification device shown in Fig. 1 drawn on an enlarged scale.

Fig. 4 is a vertical sectional view taken on the line 4—4 of Fig. 3.

Fig. 5 is a plan view of the blank which is used in constructing the identification device.

Fig. 6 is a plan view similar to Fig. 3 but illustrating an identification device constructed in accordance with a modified form of this invention.

Fig. 7 is a plan view similar to Fig. 6 but illustrating the parts in a slightly different position.

Fig. 8 is an end elevation view looking in the direction of the line 8—8 of Fig. 6.

- 5 The galley identification holding device in accordance with this invention includes a sheet metal body of substantially U-shape, with its arms indicated by reference numerals 10 and 11, and its joining bottom wall by numeral 12. The bottom 12 is formed with an opening 13 which extends substantially from end to end. Lug portions 14 are bent upwards from the end portions of the opening 13 and extend upwards to approximately the top edges of the arms 10 and 11. 10 The arms 10 and 11 are formed with small cutouts 15 at the sides extended inwards from the bottom edges thereof forming finger grips by which the body may readily be gripped when it is desired to remove the device from a galley.
- 15 20 The identification device is provided with an integral jaw gripping portion adapted to grip the side wall 16^a of a galley tray 16. The gripping device is characterized by a jaw portion 17 which extends laterally from one of the arms of the U-shaped body, more specifically from the arm 10. This jaw portion extends substantially at right angles across the rear end of the other arm 11 of the U-shaped body. Its outer end is formed with a rearwardly turned edge portion 17^a which is adapted to engage the inner face of the wall 16^a of the galley to grip the wall as hereinafter more fully explained. An inverted U-shaped portion 18 continues from the rear end of the bottom wall 12 of the U-shaped body. More specifically this U-shaped portion 18 has a front arm 18^a which is connected at its bottom edge with the rear end of the bottom wall 12 of said U-shaped body. The arm 18^a extends upwards and connects with a downwardly extending arm 18^b. 25 30 35 40 45 50 55 These arms 18^a and 18^b sandwich the jaw portion 17 forming a complementary jaw portion for engaging the other face of the side wall 16^a of the galley.

In Fig. 1 the identification device is shown mounted on the galley. It should be noted that it is engaged on the side wall 16^a of the galley in such a fashion that the jaw portion 17 extends along the inner face of the wall 16^a, and so that the complementary jaw portion 18 engages over the top edge of the wall 16^a. The arm 18^b of the jaw portion 18 engages the outer face of the wall 16^a and cooperates with the arm 17 for firmly holding the identification device in position. The arrangement is such that the identification device may be forced forwards or rearwards along

the wall 16^a to any desired position. Consequently it may be placed so that the arm 10 engages against the top of a galley of type mounted in the galley tray. It serves to hold the galley of type in position. An identification slug, or type 16^b may be placed between the arms 10 and 11 and through the opening 13 to identify the galley of type.

In Fig. 5 a blank has been illustrated which is used for constructing the identification device. This blank comprises a rectangular sheet of metal which has been stamped with certain openings and certain slots and which thereafter may be bent in a certain way to produce the identification device. The blank shown in Fig. 5 has a side portion 10', another side portion 11' and an opening 13' between these side portions. The blank has areas 12' at the ends of the opening 13' which will form the bottom wall of the U-shaped body when the identification device is formed. Lugs 14' extend inwards from the inner ends of the wall portions 12'. The opening 13' has several semi-circular cutout portions 15' along its sides. A portion 17' continues from one of the ends of the arm portion 10' for forming the jaw 17 of the device. A portion 18' continues from one of the ends of one of the portions 12' for forming the complementary jaw 18.

The blank shown in Fig. 5 may be formed into the identification device by bending the side arm portions 10' and 11' upwards along the lines AB and CD. The lugs 14' are bent upwards along the line EF. The lug portion 17' is bent at right angles to the arm portion 10' along the line GA. The tip of the lug portion 17' is bent along the line HI to form the jaw edge portion 17^a. The portion 18' is bent along the lines AC, JK and LM to form the inverted U-shaped complementary jaw portion.

In Figs. 6 to 8 inclusive, a modified form of the invention has been disclosed which distinguishes from the prior form in the provision of a U-shaped slide 20 which is set into the U-shaped body of the holder. This slide 20 has an opening 21 in its bottom wall. The side walls of the slide 20 are indicated by reference numerals 20^a and 20^b. The bottom wall is indicated by numeral 20^c. This bottom wall 20^c is located only at the front end of the U-shaped slide. A lug portion 22 is bent upwards from the inner end of the bottom wall 20^c and is adapted to engage against the front face of the lug portion 14 when the slide 20 is in its retracted position as illustrated in Fig. 6.

The rear end portions of the arms 20^a and 20^b are joined together as a unit by a removable joiner 24. This joiner 24 comprises a strip of material which has dove-tailed tongue portions 25 engaging complementary grooves formed in the inner faces in the side walls 20^a and 20^b of the U-shaped slide. The arrangement is such that the joiner 24 may be forced upwards out from the grooves 25 to disconnect the arms 20^a and 20^b. The joiner 24 is located forwards of the rear ends of the side arms 20^a and 20^b so that in the retracted position of the U-shaped slide, the joiner 24 is immediately adjacent the front face of the rear lug 14, as illustrated in Fig. 6.

The bottom edge portions of the side arms 10 and 11 of the U-shaped body are formed with outwardly bulged portions 27 forming grooves on the inner faces thereof. The bottom portions of the side arms 20^a and 20^b of the U-shaped slide are formed with similarly projecting portions 28 engaging these grooves. The arrangement is such that these projecting portions serve to slidably

connect the U-shaped slide and the U-shaped body of the device.

The identification holding device in accordance with this form of the invention is used substantially in the same way as the prior form. It is mounted upon one of the side walls of the galley and may be moved forwards and rearwards along this wall as desired. However, when it is necessary to extend the length of the holding device so as to extend over extra long slug or over two rows of slugs in the galley, it is merely necessary to grip the U-shaped slide 20 and move it to an extended position as desired. It is shown partially extended in Fig. 7. The slide 20 may be removed from the U-shaped body of the holding device by first removing the joiner 24. Then the slide 20 may be pulled out frontwards from the end of the body.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A galley identification holding device, comprising a sheet metal body of substantially U-shape having its bottom formed with an opening extending to a short distance of the ends thereof, one of the ends of the arms of said U-shape continuing into a laterally extending jaw portion for engaging one face of the side wall of a galley tray, and the bottom of said U-shape continuing into an inverted U-shaped portion the arms of which straddle said jaw portion forming a complementary jaw portion for engaging the other face of the side wall of said galley tray.

2. A galley identification holding device, comprising a sheet metal body of substantially U-shape having its bottom formed with an opening extending to a short distance of the ends thereof, one of the ends of the arms of said U-shape continuing into a laterally extending jaw portion for engaging one face of the side wall of a galley tray, the bottom of said U-shape continuing into an inverted U-shaped portion the arms of which straddle said jaw portion forming a complementary jaw portion for engaging the other face of the side wall of said galley tray, and end lugs upon the ends of the opening in the bottom of said U-shape body and extending upwards to substantially the top edge of the side arms of the body.

3. A galley identification holding device, comprising a sheet metal body of substantially U-shape having its bottom formed with an opening extending to a short distance of the ends thereof, one of the ends of the arms of said U-shape continuing into a laterally extending jaw portion for engaging one face of the side wall of a galley tray, and the bottom of said U-shape continuing into an inverted U-shaped portion the arms of which straddle said jaw portion forming a complementary jaw portion for engaging the other face of the side wall of said galley tray, and openings formed in the side arms of said U-shaped body to facilitate gripping the body.

4. A galley identification holding device, comprising a sheet metal body of substantially U-shape having its bottom formed with an opening extending to a short distance of the ends thereof, one of the ends of the arms of said U-shape con-

tinuing into a laterally extending jaw portion for engaging one face of the side wall of a galley tray, and the bottom of said U-shape continuing into an inverted U-shaped portion the arms of which straddle said jaw portion forming a complementary jaw portion for engaging the other face of the side wall of said galley tray, said first mentioned jaw having its outer end turned inwards to facilitate the gripping operation thereof.

5. A gallery identification holding device, comprising a sheet metal body of substantially U-shape having its bottom formed with an opening extending to a short distance of the ends thereof, one of the ends of the arms of said U-shape continuing into a laterally extending jaw portion for engaging one face of the side wall of a galley tray, the bottom of said U-shape continuing into an inverted U-shaped portion the arms of which straddle said jaw portion forming a complementary jaw portion for engaging the other face of the side wall of said galley tray, a U-shaped slide set into said U-shape body and having an open bottom through which said lugs project, and removable joiner connecting the side arms of said slide.

6. A galley identification holding device, comprising a sheet metal body of substantially U-shape having its bottom formed with an opening extending to a short distance of the ends thereof, one of the ends of the arms of said U-shape continuing into a laterally extending jaw portion for engaging one face of the side wall of a galley tray,

- the bottom of said U-shape continuing into an inverted U-shaped portion the arms of which straddle said jaw portion forming a complementary jaw portion for engaging the other face of the side wall of said galley tray, a U-shaped slide set into said U-shape body and having an open bottom through which said lugs project, and removable joiner connecting the side arms of said slide, the bottom edge portions of the side arms of said body and slide being provided with a projecting portion forming a slide connection between these parts.
7. A galley identification holding device, comprising a sheet metal body of substantially U-shape having its bottom formed with an opening extending to a short distance of the ends thereof, one of the ends of the arms of said U-shape continuing into a laterally extending jaw portion for engaging one face of the side wall of a galley tray, the bottom of said U-shape continuing into an inverted U-shaped portion the arms of which straddle said jaw portion forming a complementary jaw portion for engaging the other face of the side wall of said galley tray, a U-shaped slide set into said U-shape body and having an open bottom through which said lugs project, and removable joiner connecting the side arms of said slide, and comprising a strip of material having tongue portions along its edges and engaging complementary grooves formed upon the inner sides of the side arms of said U-shaped body.

JOSEPH J. SCHIMMEL.
